HIS ATTORNEY.

UNITED STATES PATENT OFFICE

IRVING NELSON BENSON, OF MELROSE, MASSACHUSETTS, ASSIGNOR TO INGERSOLL-RAND COMPANY, OF JERSEY CITY, NEW JERSEY, A CORPORATION OF NEW JERSEY

CARRIAGE FOR SPIKE DRIVERS

Application filed December 12, 1929. Serial No. 413,637.

This invention relates to carriages, but more particularly to a carriage adapted to be attached to devices used in connection with railroad construction, as for instance, a spike extractor or like mechanism which is adapted to be moved along the track from tie to tie in accordance with the exigencies of the work.

One object of the invention is to eliminate the necessity of manually lifting the spike extractor from one tie to the other, and another object is to facilitate the operation of locating the spike extractor with respect to the spike.

Other objects will be in part obvious and in part pointed out hereinafter.

In the drawing illustrating the invention and in which similar reference characters refer to similar parts,

Figure 1 is an elevation partly in section of a spike extractor equipped with a carriage constructed in accordance with the practice of the invention, and

Figure 2 is a plan view partly in section of a detail and taken through Figure 1 on the line 2—2 looking in the direction indicated by the arrows.

Referring more particularly to the drawing, A designates generally a spike extractor of a known type having a frame B and the spike extracting element, such as a pair of jaw members C which may be suitably actuated for gripping and withdrawing a spike D from a tie E by a fluid actuated piston F.

The piston F is disposed within a cylinder G and is operatively connected to the jaws C by means of a rod H, and toggle elements J which are interposed between the rod H and the jaws C.

The spike extractor may be provided with the usual handles K whereby said extractor may be manipulated and guided with respect to the work.

The parts so far described form no part of the present invention and are herein shown merely for the sake of illustrating one mode

of the application of the invention of which the following is a description.

In accordance with the present invention means are provided to protect the operator against the necessity of bodily lifting track laying devices, such as the spike extractor, from one tie to the other. To this end a pair of arms L are pivotally connected, as by means of pins O, to the opposite sides of the frame B. On the free ends of the arms L are wheels P which may be attached to the arms by means of bolts Q so arranged as to also act as axles for the wheels P. Preferably the wheels P are provided with flanges R at their ends to engage the sides S of a rail T which the spike D serves to secure to the tie E.

In order to normally hold the extractor retracted with respect to the wheels so that the lowermost extremities of the extractor, as for instance, the jaws C may pass readily over the ties E in the absence of manual pressure in a downwardly direction upon the handles K, rods V pivoted at one end to the arms extend upwardly in the direction of the cylinder G and are slidably guided by laterally extending guide plates W which may be suitably secured to the frame B.

On each rod V are arranged a pair of cup like members X and Y which serve as seats for springs Z and b disposed about the rods V. The springs Z and b are arranged concentrically with respect to each other and are of the compression type so that they constantly tend to bodily raise the extractor with respect to the wheels P.

In order that the tension of the springs Z and b may be varied the rods V are provided with threaded portions c for the accommodation of nuts d whereon the members X are seated.

In practice, whenever it is desired to extract a spike D from a tie the extractor A may be wheeled into substantially the proper position so that the jaws C will, when open,

lie on opposite sides of the spike D. If then pressure be applied to the handles K of the extractor the springs Z and b will be compressed so that the jaws C may be lowered 5 into a position to enable them to engage the head of the spike D.

After the spike has been removed the pressure against the handles K may be relieved and the springs Z and b will then raise 10 the extractor A so that the entire apparatus may be wheeled along the rail T to another tie.

The present invention has been found to be extremely desirable for use on apparatus 15 of this type, particularly where, as that illustrated, the apparatus is of considerable weight and where ordinarily more than one operator is required to lift it from one working position to another.

20 By equipping the extractor with a carriage, such as that illustrated, the extractor requires only one attendant for its operation and the work of removing spikes may be greatly expedited for the reason that the 25 extractor may be readily shifted along the track and into the proper operative position without necessitating the simultaneous supporting and guidance of the apparatus by the operator.

30 I claim:

1. In combination with a spike extractor having a frame, of a pair of wheels for the extractor, arms pivoted to the frame and forming mountings for the wheels, rods secured at one end to the arms and being guided at their other ends by the frame, and springs on the rods acting against the frame to lift the extractor relatively to the 35 wheels.

40 2. In combination with a spike extractor having a frame, of a pair of wheels for the extractor, arms pivoted on opposite sides of the frame and forming mountings for the wheels, rods pivoted at one end to the arms 45 and being guided at their other ends by the frame, springs on the rods acting against the frame to lift the extractor relatively to the wheels, and means for varying the tension of the springs.

50 3. In combination with a spike extractor having a frame, of a pair of wheels for the extractor and having flanges to engage the sides of a rail, arms pivoted at one end to the frame and at the other end to the wheels, 55 rods pivoted at one end to the arms, guides on the frame to slidably receive the other ends of the rods, spring seats carried by the rods, springs acting against the spring seats and the guides to raise the extractor relatively to the wheels, and means for varying the 60 tension of the springs.

4. A tool carrier comprising a frame, a pair of arms in hinged relationship to the frame, a wheel at the outer end of each arm, 65 and spring means acting between an inter-

mediate point on each arm and the frame to lift the frame relative to the wheels.

5. A tool carrier comprising a frame, a pair of arms extending therefrom and pivoted thereto, wheels mounted on the outer 70 end of the arms, and means acting between an intermediate point on each arm and the frame to lift the frame relative to the wheels.

In testimony whereof I have signed this 75 specification.

IRVING NELSON BENSON.
